UNITED STATES PATENT OFFICE.

LOUIS L. CORBETT, OF ATLANTA, GEORGIA.

MAGAZINE-GUN.

SPECIFICATION forming part of Letters Patent No. 664,929, dated January 1, 1901.

Application filed December 14, 1899. Serial No. 740,295. (No model.)

To all whom it may concern:

Be it known that I, LOUIS L. CORBETT, a citizen of the United States, residing at Atlanta, in the county of Fulton and State of Georgia, 5 have invented certain new and useful Improvements in Magazine-Guns; and I do hereby declare the following to be a full, clear, and exact description of the invention, such as will enable others skilled in the art to which it app-10 pertains to make and use the same.

This invention relates to firearms in general, and more particularly to that class known as "magazine-rifles," one object of the invention being to provide a lock mechanism which 15 will operate to successively receive the cartridges from the magazine, then place them in the firing-chamber, then strike the cap, and finally eject the empty shell.

A further object of the invention is to provide a construction in which the entire mechanism may be manipulated to perform its several functions by the operation of a single trigger.

Further objects of the invention are set 25 forth in the following specification.

In the drawings forming a portion of this specification, and in which like characters of reference indicate similar parts in the several views, Figure 1 is a side elevation of a magazine-rifle constructed in accordance with the present invention. Fig. 2 is an enlarged detail elevation showing the lock-plate with the mechanism of the lock in its normal position after the cartridge is exploded, a portion of 30 the magazine being in section. Fig. 3 is a view similar to Fig. 2 and showing the positions of the parts when the trigger is first drawn to raise a cartridge into line with the bolt and the firing-chamber. Fig. 4 is similar 35 to Fig. 2 and showing the position of the parts when the trigger is first released. Fig. 5 is a sectional view showing a portion of the bolt, and the extractors carried thereby for drawing the shell from the firing-chamber. Fig. 40 6 is a view similar to Fig. 5 and showing the positions of the parts when the shell is ejected.

Referring now to the drawings, 10 represents the stock of a gun, and 11 the barrel, and in which stock is mounted a lock carried by a 15 frame 12. This frame is preferably formed integral with the barrel. At the front upper and lower edges of the frame are formed

flanges 13, 13', and 14, respectively, and in the front flange 13, through which the bore of the barrel 11 opens, there opens also the magazine 15, which is of the common tubular form and contains a follower 16, operated by a helical spring 17, which acts to press the cartridges to pass successively from the magazine to the receiving-chamber of the lock. 55

The receiving-chamber is formed by a passage formed transversely of the inner face of the frame 12 adjacent to the end flange 13 and separated therefrom by a shoulder 18. A corresponding shoulder 20 is formed on the 60 inner face of the flange 14 at the opposite side of the magazine. Opening therefrom and between the shoulders is disposed a carrier 21, adapted for vertical reciprocation. This carrier has a curvilinear longitudinal recess in 65 its upper edge, one side of which is higher than the other side.

In the frame 12, at the upper end of the receiving-chamber, is formed a discharge-opening 24, through which the empty shells as 70 they are withdrawn from the firing-chamber are discharged.

In the inner face of the flange 13' of the frame is formed a slot 25, which communicates at its forward end with the receiving-chamber and is in alignment with the bore of the gun-barrel. In this slot 25 is slidably arranged a bolt 26, which is adapted to engage a cartridge after it has been raised by the carrier and force it into the firing-chamber 27. 80 This bolt also contains a loose longitudinally-disposed firing-pin 28, which projects from both ends of the bolt and is adapted for engagement by a hammer hereinafter described. 85

In order to reciprocate the bolt 26 and also 90 the carrier, a trigger 29 is pivoted at its upper end to the frame 12 and is held normally in its forward position by means of a V-spring 30, bent upon itself to surround a screw 31 in the frame, after which its ends 32 and 33 95 are curved outwardly, the end 33 lying against a stop 34 upon the frame, while the opposite end engages the trigger below its pivot and above the finger-piece 35, which extends outwardly through the trigger-slot in the gun-stock in the usual manner. The trigger has a recess 36 just above the finger-piece 35, and in this recess is disposed one end of a link 37, having a longitudinal slot 38. In this longi- 100

tudinal slot lies a screw 39, engaged with a perforation in the recess 36, the head of the screw lying against the opposite face of the link to hold it from outward displacement.

5 Thus it will be seen that as the trigger is moved backward and forward the link will be reciprocated, but that the trigger will have an amount of lost motion with respect to the link. The opposite end of the link 37 is pivoted to a lever 40, which in turn is pivoted to the frame by means of a screw 41, the upper end of the lever 40 having a link connection 42 with the recess 43 in the bolt 26. Thus when the trigger is drawn rearwardly to the 15 limit of its motion against the tendency of the spring 30 the bolt 26 will be drawn rearwardly, and when the trigger is released the spring 30 will return the bolt to its original position. (Shown in Fig. 2 of the drawings.)

20 When the bolt is in its forward position, the carrier is in its lowermost position (shown in Fig. 2) with a cartridge resting thereon. When the bolt is drawn rearwardly, the carrier is raised to bring the cartridge in line 25 with the firing-chamber, so that when the bolt is pressed forward it will press the cartridge into the firing-chamber. In order to thus operate the carrier, a recess 44 is formed in a side face of the lever 40 and lying on both 30 sides of the pivot-screw 41, and in this recess and upon this screw is pivoted a lever 45, the opposite end of which is pivoted to a link 46, which in turn is pivoted in a slot 47 in the carrier 21. The lever 45 extends slightly beyond its pivot and is adapted for engagement 35 alternately at opposite sides of its pivot by lugs 48 and 49 upon the inner face of the lever 40 and at the lower corners thereof. Thus as the lever 40 is rocked rearwardly by the 40 backward movement of the trigger the lug 48 will engage the lever 45 and will lift it, and thus raise the carrier. It is of course necessary that the carrier remain raised until after the bolt has engaged the cartridge and 45 started it into the firing-chamber, and for this purpose a flat spring 50 is provided and which has a projection 51, which is adapted to enter a recess 52 in the lever 45, adjacent its pivot, when the lever is in a position to 50 hold the carrier elevated. Thus when the trigger is moved forwardly the carrier does not drop until the lever 40 is rocked forwardly to an extent sufficient to engage the lug 49 with the lever 45 and move the notch thereof 55 from engagement with the projection 51 of the spring 50, when further movement of the lever 40 will cause the carrier to move downwardly.

In order to lock the bolt against rearward 60 movement under the influence of the explosion of the cartridge, a finger 55 is pivoted upon the pivot of the trigger 29, and fixed to the trigger is a flat spring 56, the free end of which bears against the rear end of the finger 65 and normally holds it yieldably in position to lie with its free end adjacent the rear end of the breech-bolt. When the trigger is rocked

through that part of its path in which it has lost motion with respect to the link 40, the finger is moved from behind the bolt, so that 70 when the trigger is further moved the bolt may be drawn rearwardly, as above described. As the bolt moves rearwardly the trigger moves downwardly and out of the way. This rearward movement of the bolt 75 26 acts to press the hammer backwardly and cock it. When the trigger is moved forwardly to push the bolt forwardly, there is a tendency to raise the finger 55 to its operative position; but as it rests with its free end in 80 this position against the under side of the bolt the finger is not raised, but the spring 56 is pressed, so that when the bolt is pushed to the limit of its forward movement the spring 85 acting upon the finger forces its free end upwardly to engage behind the bolt, as above described. When the trigger is again pulled, it first draws finger 55 down out of the way, at which time pin 39 reaches the end of slot 38, and continued movement of the trigger 90 draws the bolt backwardly.

The hammer is pivoted in a longitudinal recess 59 in the frame and when in its operative position engages the firing-pin in the breech-bolt. A foot 60 is formed upon the 95 lower end of the hammer, and upon this foot rests one end of a V-shaped spring 66, which is disposed in the recess 59 and bears at its opposite end against one wall thereof. The breech-bolt in its rearward movement presses 100 the hammer rearwardly until its cocking-notch 60^a receives the sear 61, which is pivoted in the recess 59 and is held yieldably in the direction of its operative position by means of a spring 62. The sear 61 has an engaging 105 edge 63 at one end, while its opposite end passes under the trigger 29 and has a lateral projection 64 lying beyond the rear face of the trigger and in the path of a lug 65 upon the trigger. This projection is so positioned 110 that as the trigger is initially moved rearwardly and before the finger 55 moves from behind the bolt 26 the lug 65 engages the projection 64 and moves the sear from engagement with the cocking-notch of the hammer, thus allowing the spring 66 to throw the 115 hammer against the firing-pin in the bolt 26 to explode the cartridge.

In Figs. 5 and 6 of the drawings there is shown a form of shell-ejector in which extractors 80 and 81 are mounted upon opposite sides of the bolt and projecting forwardly thereof to engage the rim of the shell when the bolt is moved backwardly. These extractor-claws snap over the rim of the shell, 120 and then when the bolt is drawn they draw the shell from the firing-chamber. A spring-finger 84 is fixed to the frame 12 directly opposite to the opening 24, the free end of the spring-finger extending in the direction of the 125 firing-chamber and in the path of movement of the shell from the firing-chamber. When the bolt is pressed forward, it engages this spring 84 and presses it to one side. When

the bolt is drawn rearwardly to extract the shell, the spring 84 falls outwardly and knocks the shell from the fingers 80 and 81 and through the opening 24.

5 Having thus described my invention, what I claim is—

1. In a magazine-gun, the combination with a magazine and a firing-chamber, of a bolt adapted to press the cartridges into the firing-chamber, a carrier adapted to receive the cartridges from the magazine and move them into operative relation to the bolt, a trigger, connections between the trigger and carrier for operating it, connections between the trigger and bolt for operating the latter, a stop carried by the trigger for engagement with the bolt to hold it operative, a hammer in the path of the bolt to receive motion therefrom, to cock the hammer, a sear adapted to engage the hammer to keep it cocked, said sear lying in the path of movement of the trigger for movement to release the hammer and a firing-pin adapted for engagement by the hammer.

2. In a magazine-gun, the combination with a magazine and a firing-chamber, of a bolt adapted to engage the cartridges and press them into the firing-chamber, a carrier adapted to receive the cartridges and raise them into operative relation to the bolt, a trigger connected with the bolt and carrier to operate them, said trigger having lost motion with respect to the carrier and bolt, a firing-pin, a hammer adapted to engage the firing-pin and lie in the path of movement of the bolt, a sear for the hammer to hold it cocked, said sear lying in the path of lost motion of the trigger for operation thereby, and a stop carried by the trigger for movement into and out of operative relation to the bolt, said stop being adapted to hold the bolt in operative position.

3. In a magazine-gun, the combination with a bolt, of a trigger operatively connected therewith to withdraw the bolt and having lost motion with respect to the bolt, said connections including a lever, a carrier connected with the lever and with respect to which the lever has lost motion, whereby the bolt will be partly operated before the carrier, a hammer, a firing-pin adapted for engagement by the hammer, means for cocking the hammer, means movable with the trigger for holding the parts immovable against recoil and with respect to which the trigger has a degree of lost motion to operate the sears and a sear adapted to engage and hold the

hammer, said sear lying in the path of lost motion of the trigger to be moved thereby to release the hammer.

4. A magazine-gun comprising a firing-chamber, a magazine, a carrier adapted to receive from the magazine and present to the firing-chamber, a bolt adapted to move the cartridges from the carrier into the chamber, a trigger connected with the bolt to operate it, connections between the bolt and carrier for operating the carrier, said bolt having lost motion with respect to said carrier, a firing-pin, a pivoted hammer adapted to engage the firing-pin and a sear adapted to engage and hold the hammer and lying in the path of movement of the trigger for movement thereby from engagement with the hammer.

5. A magazine-gun comprising a firing-chamber, a bolt movable toward and away from the firing-chamber, a trigger connected with the bolt to operate it and having lost motion with respect thereto, means connected with the trigger for presenting cartridges to the chamber for engagement by the bolt to be pressed into the chamber, a firing-pin, a hammer adapted to engage the pin and having operative relation to the bolt to be cocked thereby, a sear for the hammer adapted to engage and hold the hammer cocked, said sear lying in the path of lost movement of the trigger for operation thereby to release the hammer, and means operably connected with the trigger for movement into engagement with the bolt to hold the parts immovable against recoil.

6. A magazine-gun comprising a firing-chamber, a magazine, a carrier adapted to receive cartridges from the magazine and present them to the firing-chamber, a bolt adapted to engage and move the cartridges from the carrier to the firing-chamber, a trigger, a lever connected with the bolt, a trigger connected with the lever, a second lever operatively connected with the first lever and with respect to which the first lever has lost motion, connections between the second lever and the carrier for operating the latter, means for holding the carrier fixedly during the lost motion of the first lever, and a hammer in operative relation to the trigger.

In testimony whereof I affix my seal in the presence of two witnesses.
